UNITED STATES PATENT OFFICE

2,424,826

SEQUENTIAL ELECTRIC SWITCHING
SYSTEM

Frederick R. Jackson, Jr., Pittsfield, Mass., assignor to General Electric Company, a corporation of New York

Application June 20, 1945, Serial No. 600,602

5 Claims. (Cl. 175—375)

1

My invention relates to sequence control arrangements and particularly to an arrangement for sequentially controlling two switches so that they are alternately closed for a predetermined time interval with a predetermined time interval between successive switch closures.

One object of my invention is to provide an improved arrangement of parts whereby the time interval each switch is closed and the time interval between successive switch closures may be readily adjusted independently of each other.

My invention will be better understood from the following description when taken in connection with the accompanying drawing, the single figure of which diagrammatically illustrates an embodiment of my invention in connection with an arrangement for alternately connecting two electric circuits to a third electric circuit, and the scope of my invention will be pointed out in the appended claims.

Referring to the drawing, 1 and 2 represent two electric circuits which are arranged to be connected to a third electric circuit 3 by the switches 4 and 5, respectively. In accordance with my invention, I provide a control arrangement for the switches 4 and 5 so that the circuit 3 is alternately connected to and disconnected from the circuits 1 and 2 including a time relay 6 which controls the length of time each switch is maintained in its closed position and a time relay 7 which controls the length of time between successive switch closures. As shown, the time relay 6 is arranged to be energized when either the switch 4 or the switch 5 is closed, and the time relay 7 is arranged to be energized when both of the switches 4 and 5 are open at the same time. 8 is an auxiliary relay which, when deenergized, is arranged to be energized to effect the closing of the switch 4 in response to the time relay 7 completing its timing operation. 9 is another auxiliary relay which is arranged to be energized to effect the opening of the switch 4 in response to the time relay 6 completing its timing operation while the switch 4 is closed. The auxiliary relays 8 and 9 are arranged to complete locking circuits for themselves. The time relay 7, when it completes its timing operation in response to the opening of the switch 4, is arranged to effect the closing of the switch 5, and the time relay 6, when it completes its timing operation in response to the closing of the switch 5, is arranged to effect the opening of the switch 5 and the opening of the locking circuits of the auxiliary relays 8 and 9 so that the next completion of the timing relay 7 in response to the opening of the switch 5 initiates

2

another cycle of operation of the switches 4 and 5. A control switch 10 is provided which, when closed, renders the sequence control arrangement operative.

5 The operation of the control arrangement is as follows: When the control switch 10 is closed, an energizing circuit is completed for the time relay 7 through the contacts of the control switch 10, the contacts 11 of the open switch 4 and the contacts 12 of the open switch 5. When the time relay 7 completes its timing operation and closes its contacts 13, an energizing circuit is completed for the auxiliary relay 8 through the contacts of the control switch 10 and the contacts 14 of the auxiliary relay 8. The closing of the contacts 15 of the auxiliary relay 8 completes a locking circuit for the winding of relay 8 through the contacts of the control switch 10 and the parallel-connected contacts 16 and 17 of the time relay 6 and of the switch 5, respectively. The closing of the contacts 18 of the auxiliary relay 8 completes an energizing circuit for the operating winding of the switch 4 through the contacts 19 of the auxiliary relay 9, the parallel-connected contacts 16 and 17 of the time relay 6 and of the switch 5, respectively. The closing of 10 the contacts 15 of the auxiliary relay 8 and the contacts 16 and 17 of the time relay 6 and of the switch 5, respectively, the contacts 15 of the auxiliary relay 8 and the contacts of the control switch 10. The closing of the main contacts of the switch 4 connects the electric circuit 1 to the electric circuit 3, and the opening of the contacts 11 of the switch 4 interrupts the energizing circuit of the time relay 7. The closing of the auxiliary contacts 20 of the switch 4 completes an energizing circuit for the time relay 8 through the contacts of the control switch 10. The opening of the contacts 13 of the time relay 7 does not effect the deenergization of the windings of the auxiliary relay 8 and the switch 4 at this time because the circuits of these windings are now completed through the parallel-connected contacts 16 and 17 of the time relay 6 and of the switch 5, respectively, and the contacts 15 of the auxiliary relay 8.

45 When the time relay 6 completes its timing operation and closes its contacts 21, an energizing circuit is completed for the auxiliary relay 9 through the contacts 11 of the switch 5, the contacts 15 of the auxiliary relay 8 and the contacts of the control switch 10. The closing of the contacts 22 of the auxiliary relay 9 completes a shunt circuit around the contacts 21 of the time relay 6 so that a locking circuit is completed for the auxiliary relay 9 to maintain the relay energized after the time relay 6 subsequently opens its contacts 21. The opening of the contacts 19 of the auxiliary relay 9 interrupts the heretofore de-

scribed energizing circuit for the operating winding of the switch 4 so that the electric circuit 1 is disconnected from the electric circuit 3. The opening of the contacts 20 of the switch 4 interrupts the energizing circuit for the time relay 6, and the closing of the contacts 11 of the switch 4 re-establishes the heretofore described energizing circuit for the time relay 7.

When the time relay 7 completes its timing operation and closes its contacts 13 while both of the auxiliary relays 8 and 9 are energized, an energizing circuit for the operating winding of the switch 5 is completed through the contacts of the control switch 10 and the contacts 23 of the energized auxiliary relay 9. The closing of the main contacts of the switch 5 connects the electric circuit 2 to the electric circuit 3. The closing of the auxiliary contacts 24 of the switch 5 completes a locking circuit for the operating winding of the switch 5 through the contacts 16 of the time relay 6, the contacts 15 of the energized auxiliary relay 8 and the contacts of the control switch 10. The opening of the contacts 12 of the switch 5 interrupts the energizing circuit of the time relay 7, and the closing of the contacts 25 of the switch 5 completes an energizing circuit for the time relay 6 through the contacts of the control switch 10.

When the time relay 6 completes its timing operation while the switch 5 is closed, the opening of the contacts 16 of the relay 6 interrupts the heretofore described locking circuits for the auxiliary relays 8 and 9 and for the operating winding of the switch 5 so that the electric circuit 2 is disconnected from the electric circuit 3. The opening of the auxiliary contacts 25 of the switch 5 interrupts the energizing circuit for the time relay 6, and the closing of the auxiliary contacts 12 of the switch 5 re-establishes the energizing circuit for the time relay 7 which, after being energized for a predetermined time, initiates another closing of the switch 4 in the manner heretofore described.

It will be observed that in the arrangement shown in the drawing the length of time the switches 4 and 5 are closed may be adjusted by varying the operating time of the time relay 6 and that the length of time the two switches remain open may be adjusted by varying the operating time of the time relay 7, and any adjustment in the operating time of either time relay in no way affects the operating time of the other.

While I have, in accordance with the patent statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent in the United States is:

1. In combination, two switches, a timing device, means for effecting a timing operation of said timing device in response to both of said switches being simultaneously open, a second timing device, means for effecting a timing operation of said second timing device in response to either of said switches being closed, and means jointly controlled by said timing devices for effecting the alternate closing of said switches in response to successive timing operations of said first mentioned timing device and for effecting the alternate opening of said switches in response

to successive timing operations of said second timing device.

2. In combination, two switches, a timing device, means for effecting a timing operation of said timing device in response to both of said switches being simultaneously open, a second timing device, means for effecting a timing operation of said second timing device in response to either of said switches being closed, means for effecting the closing of a predetermined one of said switches in response to said first mentioned timing device completing its timing operation, means for effecting the opening of said predetermined one of said switches in response to said second timing device completing its timing operation while said predetermined one of said switches is closed, means for effecting the closing of the other of said switches in response to said first mentioned timing device completing its timing operation when said one of said switches is opened by said second timing device, and means for effecting the opening of said other of said switches in response to said second timing device completing its timing operation when said other of said switches is closed.

3. In combination, two switches, a timing device, means for effecting a timing operation of said timing device in response to both of said switches being simultaneously open, a second timing device, means for effecting a timing operation of said second timing device in response to either of said switches being closed, an auxiliary relay, means for effecting the energization of and the completion of a locking circuit for said auxiliary relay and the closing of a predetermined one of said switches in response to said first mentioned timing device completing its timing operation while said auxiliary relay is deenergized, means for effecting the opening of said predetermined one of said switches in response to said second timing device completing its timing operation while said predetermined one of said switches is closed, means for effecting the closing of the other of said switches in response to said first mentioned timing device completing its timing operation when said one of said switches is opened by said second timing device, and means for effecting the opening of said other of said switches and of said locking circuit in response to said second timing device completing its timing operation when said other of said switches is closed.

4. In combination, two switches, a timing device, means for effecting a timing operation of said timing device in response to both of said switches being simultaneously open, a second timing device, means for effecting a timing operation of said second timing device in response to either of said switches being closed, two auxiliary relays, means for effecting the energization of and the completion of a locking circuit for one of said auxiliary relays and the closing of a predetermined one of said switches in response to one of said timing devices completing its timing operation while both of said auxiliary relays are deenergized, means for effecting the energization of and the completion of a locking circuit for the other of said auxiliary relays and the opening of said predetermined one of said switches in response to said second timing device completing its timing operation while said one of said auxiliary relays is energized, means for effecting the closing of the other of said switches in response to said one of said timing devices completing its timing operation while both of said auxiliary relays are energized, and means for effecting the opening of

said other of said switches and the opening of all of said locking circuits in response to said second timing device completing its timing operation while both of said auxiliary relays are energized.

5. In combination, two switches, a time relay, means controlled by said switches for effecting a timing operation of said relay when both of said switches are open, a second time relay, means controlled by said switches for effecting a timing operation of said second time relay when either of said switches is closed, an auxiliary relay, a secondary auxiliary relay, means controlled by said first mentioned time relay and said second auxiliary relay for effecting the energization of said first mentioned auxiliary relay in response to said first mentioned time relay completing its timing operation when said second auxiliary relay is deenergized, a locking circuit for said first mentioned auxiliary relay, means controlled by said auxiliary relays for effecting the closing of one of said switches when said first mentioned auxiliary relay is energized and said second auxiliary relay is deenergized, means controlled by said second time relay and said auxiliary relays for effecting the energization of said second auxiliary relay in response to said second time relay completing its timing operation when

said first mentioned auxiliary relay is energized and said second auxiliary relay is deenergized, a locking circuit for said second auxiliary relay, means responsive to the energization of said second auxiliary relay for effecting the opening of 5 said one of said switches, means controlled by said second auxiliary relay and said first mentioned time relay for effecting the closing of said other switch in response to said first mentioned time relay completing its timing operation while said 10 second auxiliary relay is energized, and means controlled by said second time relay for effecting the opening of said other switch and said locking circuits in response to said second time relay completing its timing operation when said other switch is closed.
